ADJUSTABLE FURNITURE LEG CASTER CUP

Harold Adolphe Peterson, Minneapolis, Minn.

Application January 30, 1939, Serial No. 253,650

2 Claims. (Cl. 45—139)

This invention relates to a support for a furniture and particularly to a support adapted to be placed under the leg of an article of furniture. A great many articles of furniture are supported upon four legs, and it frequently happens that due to unevenness in the supporting surface or to a variation in the length of said legs that all of the legs do not contact the floor or supporting surface. This causes the article of furniture to 10 tip slightly when pressure comes upon the leg which is out of contact with the supporting surface.

It is an object of this invention to provide an adjustable device which may be used to support 15 one or more legs of an article of furniture such as a table, chair, bed, etc. so that all of the legs will be in firm contact with the supporting means.

It is a further object of the invention to provide a very simple and efficient adjustable support for 20 a leg of an article of furniture, one that can be easily and inexpensively made and which can be easily positioned and quickly positioned for use.

It is more specifically an object of the invention to provide an adjustable device for a leg of 25 an article of furniture comprising a member adapted to rest upon the floor and having an opening therein together with a second member constructed and arranged to be disposed at different heights in said opening and having a 30 surface for supporting the leg of the article of furniture, said second member being provided with simple and efficient means for positioning it within said first mentioned member.

These and other objects and advantages of the 35 invention will be fully set forth in the following description made in connection with the accompanying drawing in which like reference characters refer to similar parts throughout the several views and in which:

40 Fig. 1 is a top plan view of the device;

Fig. 2 is a vertical section taken on line 2—2 of Fig. 1 as indicated by the arrows, the leg of an article of furniture being indicated in dotted lines;

45 Fig. 3 is a top plan view of a portion of the device;

Fig. 4 is a central vertical section of the part shown in Fig. 3;

50 Fig. 5 is a top plan view of a modified form of the device;

Fig. 6 is a vertical section taken on line 6—6 of Fig. 5 as indicated by the arrows;

Fig. 7 is a vertical section taken on line 7—7 of Fig. 5 as indicated by the arrows; and

55 Fig. 8 is a vertical section taken through a part

of the device substantially in the plane of line 7—7 of Fig. 5.

Referring to the drawing a device is shown comprising a member 10 of general cylindrical form, the periphery of which in the embodiment of the invention illustrated is shown as slightly curved in a vertical plane and decreasing in diameter toward the top of said member. Member 10 is provided with a central opening 10a and at its bottom is shown as having a counterbore 10b of small depth. A plate 13 is pressed or otherwise held in counterbore 10b, and with flange 10c surrounding said counterbore, will engage the floor or other supporting surface. The member 10 is interiorly threaded as indicated at 10d. A 15 member 11 is provided having a threaded periphery 11a of such diameter that member 11 can be screwed or threaded into the central opening in member 10. Member 11 is made slightly of cup shape having a depressed top surface 11b which 20 will form the supporting surface for the leg of an article of furniture, said leg being indicated in Fig. 2 as 12. Member 11 has formed thereon and circumferentially spaced about its thicker portion, a plurality of upstanding lugs 11c illustrated as 25 three in number. Lugs 11c, as clearly shown in Figs. 1 to 4, taper toward their upper ends both in thickness and width.

In operation, member 11 will be threaded into member 10 and by grasping the portions 11c with the fingers member 11 can be rotated in member 10 to bring the same to the desired position or height therein. This position will be determined by the position of the bottom of leg 12 which it is desired to support. The leg 12 will then rest firmly on the top surface 11b and will extend between the members 11c. In the use of the device it may be only necessary to use the same under one leg of an article of furniture having four legs. Devices which are similar in appearance but not adjustable could be placed under three of the legs and the adjustable device described used only under the fourth leg. The article of furniture would then be firmly supported on all four legs. It will be seen that member 11 can be very easily and quickly moved to the desired position by engaging the lugs 11c.

In Figs. 5 to 8, a modified form of the invention is shown comprising a member 14. This member is in the form of a three-sided figure having its sides at right angles. The outer surface of the three sides is formed on a curve extending inwardly toward the top of member 14. The inner surfaces of the three sides are substantially vertical and are provided with a plurality of in- 55

wardly extending ribs 14a of V-shape in cross section separated by similar V-shaped grooves. A second member 15 is provided of general square or rectangular shape and this member has on three sides thereof ribs 15a of V-shaped form separated by V-shaped grooves, which ribs and grooves correspond to the ribs and grooves in member 14. The structure is such that member 15 can be slidably moved into the open side of member 14, the ribs 15a fitting into the grooves on the two sides of member 14. When member 15 is fully inserted, the ribs 15a on its third side will engage the grooves on the closed end of member 14 so that member 15 will be supported on three sides. It will be noted that the ends 14b of the parallel sides of member 14 at its open side are formed on an angle of 45 degrees. Vertical grooves 14c are formed in said ends 14b and are transversely aligned respectively. A closing member 16 is provided, the same having sides adapted to fit within the ends 14b and having projecting ribs 16a arranged to fit within the grooves 14c. Member 16 can thus be moved vertically into position and is of slightly less height than member 14. Member 16 will slide down in front of member 15 and substantially engage with the front or smooth side of member 15. Member 16 is provided with a groove or recess 16d at its bottom which forms a comparatively narrow flange 16e. A plate 17 is pressed in or otherwise held in groove or recess 16d and with flange 16e will engage the floor or supporting surface. Plate 17 will also support member 16. Member 15 is provided with a depressed surface 15b which will form the support for the leg of the article of furniture.

With the described construction it will be seen that member 15 can be disposed at different heights or in different positions in member 14. It is only necessary to remove member 16 in order that member 15 may be so positioned. Member 15 of course, will be positioned so that the desired firm support is secured for the leg of the article of furniture.

From the above description it will be seen

that I have provided an extremely simple and efficient device adapted to support the leg of an article of furniture and furnish a firm support for such an article having four or more legs. The device forms a convenient and ornamental article. The same can be made from metal, glass or can be made of one of the modern plastic compositions. If desired, a soft covering (not shown) may be applied to the bottom of plates 13 and 17 and the surrounding flanges 10c and 14e. The device will be nicely colored and finished and can thus be made to harmonize with the finish of the furniture. It will be apparent that the device will have a high degree of utility for the purpose intended.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. An adjustable support for a leg of an article of furniture having in combination, a member adapted to rest upon the floor and having a central opening therethrough, said opening being threaded, a second member of much less height than said member threaded in said opening and arranged to be disposed at different positions within the same and having a top surface adapted to support said leg, a plurality of circumferentially spaced lugs extending upwardly from said second member adjacent the outer edge thereof between which said leg will be disposed, said lugs forming a handle means by which said second member may be engaged from above by the fingers of the operator to turn and adjust the same.

2. The structure set forth in claim 1, said lugs 40 tapering toward their upper ends, said first mentioned member having a shallow cylindrical depression in its bottom and a plate disposed in said depression closing said opening.

HAROLD ADOLPHE PETERSON. 45
